UNITED STATES PATENT OFFICE

TALMA T. GREENWOOD, OF EAST TEMPLETON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

METHOD AND APPARATUS FOR PROVIDING THE CASINGS OF ELECTRICAL APPARATUS WITH INERT ATMOSPHERES

Application filed December 1, 1926. Serial No. 152,047.

This invention relates to means for providing the casings of oil immersed electrical apparatus with an atmosphere which is inert with respect to the atmosphere and to the oil and the gases and vapors of the oil, and for preventing fires and explosions in such casings.

Electric switches and transformers, for instance, are contained in casings and immersed 10 in oil or other equivalent liquid for the purpose of providing a high quality of insulation between conductors at different potentials and also for the purpose of rapidly extinguishing the circuit-interrupting arc of an 15 electric switch, and an arc which may sometimes occur under the oil in a transformer.

When the contact members of an oil-immersed electric switch are separated under load, large amounts of oil gases and vapors 20 may be generated by the circuit-interrupting arc. This also is the case when an arc occurs under oil in a transformer casing. It is common practice to provide switches and 25 transformers with gas expansion spaces above the oil into which the oil gases and vapors can expand, when formed, whereby to keep down the internal pressure of the casing. Ordinarily air is present in the gas 30 expansion space, either entering the casing through leaks in the casing joints or through especially provided vent passages that are employed to permit the casing to breathe under variations of the volumes of the elastic 35 fluid and liquid contents thereof under temperature and barometric variations.

When oil gases and vapors and air are present within the enclosing casing in suitable proportions, the mixture is combustible and will explode when ignited due to heat 40 of the arc, a static discharge or other means, and may seriously damage the casing and apparatus. The insulating oil or other liquid, also, commonly is slowly auto-oxidizable in the presence of the oxygen of the air and 45 thickens or sludges, thereby impairing the usefulness of the liquid.

To remedy or avoid the aforesaid difficulties it has been proposed to maintain an inert, or more particularly, a substantially oxygen-free atmosphere within the casing and above

the oil by the use of a material which reacts chemically with the oxygen of the air to remove it from the gaseous atmosphere within the casing. The materials commonly suggested have been phosphorus, the alkali metals and the like wherein the oxygen and the material unite to form an oxide of the material. In all cases the oxide has been a permanent oxide and the material, after having been oxidized, has been unfit for further service and must be replaced by fresh material. The materials heretofore proposed have been fairly expensive, and charges thereof must be frequently removed so that the yearly cost of maintenance of an inert atmosphere by the use of such materials is relatively great. Furthermore, if the charge is not removed when or before it is spent, the inert atmosphere is lost and is replaced by an active atmosphere, thus bringing about 55 dangerous or at least undesirable conditions.

It is an object of this invention to provide an oil-immersed electrical apparatus with means to create an inert atmosphere therein by means which is not permanently destroyed 60 in the process of removing the oxygen and which can be re-activated when its oxygen absorbing or combining ability is temporarily exhausted, whereby greatly to reduce the expense of maintaining the inert atmosphere.

A further object of the invention is the provision of an enclosed oil-immersed electrical apparatus and a temporary container for the oxygen content of the air within the apparatus enclosure, in which container the 65 oxygen is temporarily retained and is isolated from the atmosphere of the casing and from which container the oxygen can be removed to condition the container for continued service.

A yet further object is the provision of means automatically-operative to remove the oxygen content of an enclosing casing and to discharge the oxygen externally of said casing.

A further object is generally to improve the construction and operation of electrical apparatus and the production of inert atmospheres therefor.

switch embodying the invention, the switch being shown in section.

Fig. 2 is an enlarged sectional elevation of the de-oxygenating apparatus embodying the invention.

Fig. 3 is an end-view of the apparatus of Fig. 1.

Fig. 4 is a diagrammatic view illustrating the circuit connections for effecting the automatic operation of the apparatus.

Fig. 5 is a modified form of the de-oxygenating apparatus.

The electrical apparatus here shown as associated with the invention, comprises an electric switch having the enclosing casing 10 adapted to contain a body of oil in which the fixed switch members 12 and movable switch member 14 are immersed. The casing is provided with a cover 16 through which the insulated switch terminals 18 are extended. The casing is adapted to contain a gas expansion space 20 above the body of the oil. In accordance with this invention, the gas expansion space is adapted to contain an inert atmosphere which is not combustible with the gases and oil or the equivalent liquid or with the gases and vapors thereof or with air. To this end, I provide means to remove the oxygen from the gaseous atmosphere within the casing and also to remove the oxygen from air entering the casing whereby to maintain the expansion space filled mainly with nitrogen, or with an atmosphere having such a low content of oxygen that it is non-combustible. In carrying out my invention, I provide means to absorb or to unite with the oxygen, thereby to remove it from the atmosphere. Said means is further characterized by being capable of liberating the absorbed or united oxygen under suitable conditions whereby it can be used indefinitely without deterioration. The particular means I employ is preferably barium oxide, BaO. Barium oxide is characterized by its ability to absorb or combine with the oxygen of the air to form barium dioxide when heated to a suitably high temperature, as to a dark red heat. When heated to a higher temperature, or subjected to a reduced pressure, or both, the barium dioxide gives up its oxygen and is re-converted to barium oxide. I have herein utilized this principle of barium oxide to maintain an inert atmosphere within the casing of an electrical apparatus.

Fig. 5 shows a simple form of the invention wherein a charge 22 of barium oxide is disposed within a suitable container 24, the open top of which is closed by the removable cover 26. Said container is provided with an upper laterally-extended neck 28 adapted to be secured removably to the side wall of the casing 10 of the electrical apparatus and having a passage 30 therein aligned with an opening 32 in the side wall of said casing. The container 24 is also provided with a lower later-

ally-extended neck 34 having a passage 36 therein which is aligned with a lower opening 38 in said casing 10. Said container 24 is also provided with a passage 40 which is adapted to communicate with the atmosphere. The charge of oxygen-removing material is supported upon a perforated wall or screen 42 located above said passages 36 and a wall 44 disposed immediately beneath said screen 42 serves to isolate said two passages.

An electric heating coil 46 is disposed in said body of oxygen-removing material and is adapted to heat said material to a suitable temperature. As thus arranged, the heat of said coil 46 serves to set up by thermal action a circulation of the atmosphere within said casing 10 through the lower passage 36 and upwardly through the porous mass of oxygen-removing material 22 and thence through the upper passage 28 back into the casing. In its passage through the material 22, the oxygen of the gaseous atmosphere within the casing 10 is abstracted so that the remaining atmosphere consists largely of nitrogen.

The casing 10 is adapted to breathe through the opening 40 upon changes of temperature so that some of the inert gas may escape to the atmosphere upon a rise of temperature of the contents of the casing. When the pressure drops within the casing, however, air is drawn in through the passage 40 and as it passes upwardly through the material 22, the oxygen thereof is abstracted so that the gas that passes into the casing 10 is practically free from its oxygen content, or will be shortly subsequently rendered so by rapid circulation through the oxygen-removing material. The preferred form of the invention is illustrated in Figs. 2, 3 and 4 wherein means are provided not only to absorb the oxygen but subsequently to discharge the abstracted oxygen into the atmosphere. As shown in these figures, the oxygen-removing material is enclosed within a cylindrical container 50, the open top of which is provided with a removable cover 52 and the open bottom of which is provided with a removable cover 54.

Said container is secured removably to the side wall of the casing 10 and is provided with an upper passage 56 which is in register with the upper opening 32 in the side wall of said casing. Said container is also provided with a lower passage 58 which is in register with the lower opening 38 of said casing. Said container is also provided with a second passage 60 in the upper end thereof which is adapted to communicate with the atmosphere. Said passages 60 and 56 are adapted to be opened and closed alternately by means of valve members 62 and 64 respectively. Said valve members are carried upon a rod 66 which is connected with a plunger or armature 68 at one end. Said plunger is

operable within a solenoid 70 and is adapted to be moved toward the right when said solenoid is energized to effect the closing of the passage 56 and the opening of the passage 60. A spring 72 serves to urge said plunger and the valve in the opposite direction whereby normally to maintain said valve 64 open and said passage 60 closed.

The porous mass 74 of oxygen-removing material, as barium oxide, is contained within a cylindrical basket 76 which is freely movable in a vertical direction in said container 50 and is adapted to be a practically gas tight fit therein so that said basket serves as a seal to prevent direct communication between said lower passage 58 and said upper passage 56. Said basket is provided with a plurality of peripherally-disposed perforations or openings 78 in its side wall and near the bottom thereof through which the gas in said passage 58 may pass into the interior of said basket and thence upwardly through the material therein. Said basket is provided with a foraminous bottom wall 80 which is adapted to support the material. The bottom cover 54 is provided with a passage 82 therein which is adapted to communicate with the atmosphere and said passage constitutes a breather passage or opening.

An electric heating coil having the two electrically-connected heating sections 84 and 86 is disposed within said basket and is adapted to heat the material therein. The terminals 88 and 90 of said sections are flexible and are brought out through a suitable terminal block 92. A third flexible terminal 94 is also brought out from the junction between said sections 84 and 86 to said terminal block 92. Said basket 76 is supported upon a sensitive compression spring 96 which is adapted to permit the basket to move within said container 50 in response to changes in weight of the oxygen-removing material therein contained. Said basket is provided with a stem 98 which is extended freely through said bottom cover 54 and into a switch casing 100 carried by said bottom. Said stem is operatively connected with a quick-acting switch 102 of any usual or suitable construction, which switch is so arranged that it closes when the basket has been moved downwardly a predetermined distance; and said switch is adapted to open when said basket is moved upwardly a predetermined distance. The normal disposition of the parts is illustrated in Fig. 2 wherein the oxygen-removing material is in free communication with the interior of the switch casing and also with the atmosphere through the opening 82. Both sections 84 and 86 of the heater coil are adapted to be energized so that the body of material 74 is maintained at a suitable temperature to be active and to absorb or combine with the oxygen of the gaseous contents of the casing 10 and also to absorb or combine with the oxygen

of the air that may enter the container 50 through the opening 82 on its way to the interior of the casing. As the material, as barium oxide, absorbs oxygen and thereby becomes gradually converted into barium dioxide it increases in weight so that the basket 76 gradually descends within the container 50.

When the amount of absorbed or combined oxygen is sufficiently great, the basket is moved into such a position that it is caused to operate the switch 102 and close the switch circuit. The connections of the switch circuit are illustrated in Fig. 4 and are such that the solenoid 70 is energized thereby to close the passage 56 and open the passage 60. At the same time, the lower section 86 of the heating coil is operatively cut out of the circuit by being shunted by the low resistance solenoid 70. The section 84 of the heating coil thereby receives more energy and so operates to heat the barium oxide to a higher temperature, thus driving off the absorbed or combined oxygen and discharging it to the atmosphere through the passage 60. As the barium dioxide loses oxygen it decreases in weight so that the basket 76 rises within the container 50. When sufficient oxygen has been liberated, as when a large proportion of the barium oxide has been re-converted into barium oxide, the basket 76 is adapted to move upwardly a sufficient distance to effect the opening of the switch 102. The solenoid 70 is thus cut out of the circuit and the spring 72 effects the closing of the passage 60 and the opening of the passage 56 so that the normal or operative condition of the de-oxygenating apparatus is restored. Both sections of the heater coil are thus placed in service and the barium oxide cools down to that temperature at which it is active in absorbing or combining with the oxygen of the gas in contact therewith.

As thus arranged, a single charge of gas removing material serves indefinitely to maintain an inert gas within the casing 10 of the electrical apparatus. The material serves as a temporary container for the oxygen and is automatically caused to abstract the oxygen from the interior of the casing 10 and to liberate it externally of the casing.

For certain purposes the barium oxide may be replaced by some other material, as charcoal, for instance, which has the power to absorb oxygen in larger quantities than other gases of the atmosphere and to give up the absorbed gases upon elevation of pressure.

The construction may be otherwise modified without departing from the spirit of the invention.

I claim:

1. The method of providing an inert atmosphere for the casing of an electrical apparatus which consists in placing barium oxide in communication with the interior of the casing and activating the barium oxide to

cause it to combine with the oxygen in the casing and subsequently isolating the barium oxide from circulatory communication with the atmosphere of the casing, subjecting the barium oxide to such conditions as to cause it to liberate the combined oxygen free from mixture with the inert atmosphere in the casing, and subsequently restoring the barium oxide in communication with the interior of the casing.

2. The method of providing an inert atmosphere for the casing of an electrical apparatus which consists in the successive steps of placing barium oxide in communication with the interior of the casing and activating the barium oxide to cause it to combine with the oxygen in the casing and subsequently isolating the barium oxide from circulatory communication with the atmosphere of the casing when the weight of the barium oxide has increased materially due to its increased oxygen content and subjecting the barium oxide to such conditions as to cause it to liberate the combined oxygen free from intermixture with the inert atmosphere of the casing, and subsequently replacing the oxygen-free barium oxide in communication with the atmosphere of the casing.

3. The combination with the casing of an electrical apparatus, of a temporary container for the oxygen content of the atmosphere of said casing comprising a body of barium oxide and automatically operative means governed by the oxygen content of said barium oxide to place said barium oxide body alternately in and out of fluid circulatory communication with the casing-atmosphere, and means to subject said barium oxide body to varying conditions when in and out of communication with the casing atmosphere.

4. The combination of the casing of an electrical apparatus, and means to provide said casing with an inert atmosphere comprising a temporary container for the oxygen content of the casing-atmosphere, and means governed by the amount of abstracted oxygen in said container to condition said container to abstract the oxygen content of the casing-atmosphere and also to liberate the abstracted oxygen free from the inert atmosphere of said casing.

5. The combination of the casing of an electrical apparatus, and means to provide said casing with an inert atmosphere comprising a temporary container for the oxygen content of the casing-atmosphere, and automatically operative means governed by the amount of abstracted oxygen in said container to condition said container to abstract the oxygen content of the casing-atmosphere and also to liberate the abstracted oxygen free from the inert atmosphere of said casing, said temporary container including a body of barium oxide.

6. The combination of the casing of an

electrical apparatus, and means to provide said casing with an inert atmosphere, said means including a body of barium oxide, means to place said body into and also out of fluid circulatory communication with the interior of the casing, and means to heat said body to one temperature when in communication with the interior of the casing to cause said body to absorb oxygen from the casing atmosphere and to another temperature when out of communication with the interior of the casing to cause it to give up the absorbed oxygen.

7. The combination of the casing of an electrical apparatus, and means to provide said casing with an inert atmosphere, said means including an oxygen-abstracting body, means automatically operative in response to the amount of oxygen in said body to place said body into and also out of fluid circulatory communication with the interior of the casing, and means to heat said body to one temperature when in communication with the interior of the casing and to another temperature when out of communication with the interior of the casing.

8. The combination of the casing of an electrical apparatus, and means to provide said casing with an inert atmosphere, said means comprising a body of barium oxide, means to place said body into and also out of fluid circulatory communication with the interior of the casing, and means to heat said body to one temperature when in communication with the interior of the casing and to another temperature when out of communication with the interior of the casing, both the aforesaid means further characterized by being operable in response to variations in weight of said body.

9. The combination of the casing of electrical apparatus and means to provide said casing with an inert atmosphere comprising means to remove the oxygen content of said casing and automatically-operative means governed by the amount of removed oxygen arranged to govern the operation of said oxygen removing means.

10. The combination of the casing of an electrical apparatus, and a de-oxygenating apparatus associated therewith having automatically-operative means governed by the amount of oxygen abstracted alternately to place said apparatus in fluid circulatory communication with the interior of said casing and with the atmosphere outside of said casing.

11. De-oxygenating apparatus comprising a container for a mass of oxygen absorbing material, said container having a pair of gas passages and automatically-operative means governed by the amount of absorbed oxygen to open and close said passages alternately.

12. De-oxygenating apparatus comprising a container having a pair of gas passages, a

5 basket for the absorbing material movably disposed within said container and adapted to assume a position therein proportionate to the oxygen content of the oxygen absorbing material, and means controlled by said basket to open and close said passages alternately.

10 13. De-oxygenating apparatus comprising a container, a basket for absorbing material movably disposed therein and adapted to assume a position proportionate to the oxygen content of the absorbing material, an electric heater element disposed to heat the contents of said basket, and means governed by the 15 position of said basket within said container to vary the heating effect of said heating element.

14. De-oxygenating apparatus comprising a container having a passage for oxygen-free 20 gas and a passage for oxygen-laden gas, a basket for oxygen absorbing material movably disposed within said container and adapted to assume a position therein governed by the oxygen content of the oxygen absorbing 25 material, a heating element disposed to heat the contents of the basket, and means governed by the position of said basket within said container arranged to open and close said passages alternately and also to vary 30 the heating effect of said heating element.

In testimony whereof, I have signed my name to this specification.

TALMA T. GREENWOOD.
